[57] CLAIM

The ornamental design for a fan stand, as shown and
described.

DESCRIPTION

FIG. 1 is a front elevational view of a fan stand showing
our new design;

FIG. 2 is a right side elevational view thereof;

FIG. 3 is a rear elevational view thereof;

FIG. 4 is a left side elevational view thereof;

FIG. 5 is a top plan view thereof; and,

FIG. 6 is a bottom plan view thereof.

The broken line showing of environmental structure in
FIGS. 1-6, is for illustrative purposes only and forms no
part of the claimed design.**FIG. 1****FIG. 2**
